Patented Dec. 16, 1924.

UNITED STATES PATENT OFFICE.

ALBERT M. WOLTZ, OF BALTIMORE, MARYLAND, ASSIGNOR, BY MESNE ASSIGNMENTS,
TO M. L. HIMMEL & SON COMPANY, INC., OF BALTIMORE, MARYLAND, A CORPOR-
ATION OF MARYLAND.

BOLT-OPERATING MECHANISM.

Application filed October 22, 1920. Serial No. 418,660.

To all whom it may concern:

Be it known that I, ALBERT M. WOLTZ, a citizen of the United States, residing at Baltimore, State of Maryland, have invented 5 a new and useful Bolt-Operating Mechanism, of which the following is a specification.

This invention is a new and useful device for locking a door both at the top and 10 the bottom, and is an improvement upon the bolt-operating mechanism described and claimed in Letters Patent No. 1,136,498 granted April 20, 1915.

One of the objects of the invention is to 15 provide a bolt-operating mechanism of the character referred to, having a simple and efficient means for preventing retraction of the bolts when they are in locking position. A further object is to provide a key-operated 20 lock having a movable member positioned to be moved into and out of the path of movement of the handle which actuates the bolt-mechanism.

The invention will be hereinafter fully 25 set forth and particularly pointed out in the claims.

In the accompanying drawing:—

Figure 1 is a side elevation illustrating a bolt-operating mechanism constructed in accordance with the invention, parts being broken away. Figure 2 is a rear view thereof. Figure 3 is an enlarged view illustrating the locking member in its lever-engaging position. Figure 4 is a similar view showing 35 the locking member retracted.

Referring to the drawing, 10 designates a metal housing shaped to engage the stile of a door, and provided at one end with a short cylindrical shell 11, extending inwardly at 40 approximate right angles to the plane of the outer face of the housing. The handle or lever 12 which operates the bolt-actuating mechanism, is pivotally supported at one end in the housing 10, the free end thereof 45 being provided with suitable means by which it may be held by the operator, such as the ring-like portion 13. The pivot end of the handle 12 is provided with an approximate- 50 ly semi-circular segment 14, around which is passed a helical spring 15, one end of said spring being engaged with an eye 16 on the handle, the other end being secured to the housing, as shown. By this arrangement 55 the spring acts to normally hold or retain the handle in closed position within the

housing. Pivotally mounted on the same pivot pin 17 which supports the handle 12, is a bolt-actuating lever 18, extending inwardly with respect to the housing, and parallel with one side of the segment 14. Said 60 lever is provided with a slot 19, in which works a pin 20, projecting from the contiguous side of said segment. Pivotally mounted in the housing between the pivot 17 and the shell 11, is a second bolt-actuating 65 lever 21, the said levers 18 and 21 having complementary interlocking portions 22, whereby movement of the lever 18 will impart a corresponding movement to the lever 21. The upper and lower bolts 23 and 24 70 are connected with the respective levers 18 and 21. With the exception of the shell 11, the construction thus far described is identical with that illustrated and described in the patent above referred to, and operates 75 in precisely the same manner.

Mounted in the shell 11 is a lock 25, which may be of any desired construction, it being preferred, however, to employ a key-operated 80 lock of the well-known type in which removal of the key is prevented until the parts are moved to locking position. Said lock is provided with a rotatable barrel 26, the rear end of which carries a crank pin 27, which engages the slotted portion 28, of a 85 latch or locking member 29. Said latch projects through a slot in the shell 11, in a direction longitudinally of the housing 10, and is provided with an offset portion having a lip 30, positioned to engage a complementary latch-engaging portion 31, on the 90 free end of the handle 12.

In practice, the bolt-operating mechanism is actuated by means of the handle 12, in a manner fully described in said Letters 95 Patent No. 1,136,498, and which will not be repeated here. When it is desired to lock the mechanism, the barrel 26 of the lock 25 is rotated by means of its key, thereby imparting movement to the latch 29, through the medium of the crank pin 27, so as to bring the lip 30 into engagement with the part 31 of the handle 12. The key may then be withdrawn, and the handle 12 will be securely locked against movement, thereby holding the bolts 23 and 24 against withdrawal from engagement with the door casting. When it is desired to unlock the mechanism, the barrel 26 is rotated in the reverse 105 direction by means of the key, thereby with- 110

drawing the latch 29 from engagement with the handle 12, leaving the latter free, so that the bolt-operating mechanism may be actuated in the usual manner whenever desired.

The advantages of the invention will be readily apparent to those skilled in the art to which it appertains. It will be particularly noted that the bolts 23 and 24 engage the door casing immediately upon the closing of the door, and that by employing a lock 25 of the type which prevents withdrawal of the key until after locking, it will be impossible to open the door without first inserting the key and withdrawing the latch 29.

Having thus explained the nature of the invention, and described an operative manner of constructing and using the same, although without attempting to set forth all of the forms in which it may be made, or all of the forms of its use, what is claimed is:—

1. The combination with a handle pivotally supported at one end and bolt mechanism actuated thereby, of a rotatable actuator, and a rectilinearly movable latch connected to and operated by said actuator and positioned to engage the free end of said handle.

2. The combination with a handle pivotally supported at one end and bolt mechanism actuated thereby, of a rotatable actuator, and a latch connected to and operated by said actuator, said latch having a free end so disposed that it may be moved into a position overlapping the free end of said handle.

3. The combination with a handle pivotally supported at one end and a bolt mechanism actuated thereby, of a rotatable actuator, and a latch connected to and operated by said actuator, said latch being capable of an approximately rectilinear movement in a plane parallel with the longitudinal median line of said handle, whereby it may be moved into and out of engagement with said handle.

4. The combination with a handle pivotally supported at one end and bolt mechanism actuated thereby, a barrel contiguous to the free end of the handle and in alignment therewith, a rotatable actuator mounted in said barrel, and a rectilinearly movable latch operated by said actuator and positioned to engage the free end of said handle.

5. The combination with a handle pivotally supported at one end and bolt mechanism actuated thereby, of a barrel contiguous to the free end of the handle and in alignment therewith, an actuator rotatably mounted within said barrel, and a recti-

linearly movable latch connected with the inner portion of said actuator and having an offset end position to engage the free end 65 of said handle.

6. The combination with a handle pivotally supported at one end and bolt mechanism actuated thereby, of a rotatable actuator disposed at right angles and contiguous to the free end of said handle, and a rectilinearly movable latch connected with one end of said actuator and positioned to engage the free end of the handle.

7. The combination with a handle pivotally supported at one end and bolt-mechanism actuated thereby, of a latch having a slot in one end, and a rotatable actuator positioned contiguous to the other end of said handle provided with a crank pin loosely engaging said slot, whereby said latch may be moved into and out of engagement with said handle.

8. The combination with a housing provided with a cylindrical shell in one end, a handle pivotally mounted at one end in the other end of said housing, and bolt mechanism actuated by said handle, of an actuator extending through said shell, and a latch operated by said actuator and positioned to engage said handle.

9. The combination with a housing provided with a cylindrical shell in one end, a handle pivotally mounted at one end in the other end of said housing, and boltmechanism 95 actuated by said handle, of a rotatable actuator mounted in said shell, and a latch engaging one end of the actuator and having a free end positioned to engage said handle.

10. The combination with a housing provided with a cylindrical shell in one end, a handle pivotally mounted at one end in the other end of said housing, and bolt mechanism actuated by said handle, of a lock mounted in said shell and provided with a rotatable member, a crank pin carried by said rotatable member, and a latch engaging said crank pin and positioned to engage said handle.

11. The combination with a housing provided with a cylindrical shell, a handle pivotally mounted in said housing, and bolt-mechanism actuated by said handle, of a lock mounted in said shell and provided with a rotatable member, a crank pin carried by the rear end of said rotatable member, and a latch having a movable engagement with said crank pin and provided with an offset locking lip overhanging said shell 120 and positioned to engage said handle.

In testimony whereof I have hereunto set my hand.

ALBERT M. WOLTZ.
